CLAIM

The ornamental designs for a telephone handset and base, as shown and described.

DESCRIPTION

FIG. 1 is a perspective view of the telephone handset and base, with the handset shown in its position in the cradle, when not in use;

FIG. 2 is a front elevation thereof;

FIG. 3 is a rear elevation thereof;

FIG. 4 is a top elevation thereof;

FIG. 5 is a bottom elevation thereof;

FIG. 6 is a left side elevation thereof; and,

FIG. 7 is a right side elevation thereof.
